UNITED STATES PATENT OFFICE.

IRVING L. POMEROY, OF CHICAGO, ILLINOIS, ASSIGNOR TO AUTOPOINT MANUFACTURING COMPANY, OF CHICAGO, ILLINOIS, A CORPORATION OF ILLINOIS.

PENCIL.

Application filed December 8, 1922. Serial No. 605,567.

To all whom it may concern:

Be it known that I, IRVING L. POMEROY, a citizen of the United States, residing at Chicago, in the county of Cook and State of Illinois, have invented certain new and useful Improvements in Pencils, of which the following is a specification.

This invention relates to a pencil equipped with propelling mechanism interiorly of its body and operable by means exteriorly thereof for advancing into operative position a lead at one end and an eraser at the other.

The improvements of my invention are particularly applicable to a pencil having the general construction shown in Letters Patent No. 1,372,354 granted March 22, 1921, on an invention of Charles R. Keeran. More particularly this invention is concerned with a novel and improved means for locking against rotation, one of the parts contained in the lead propelling mechanism, this means also providing a bottom for certain radial chambers wherein are accommodated reserve leads.

A pencil embodying the features of this invention is shown in the accompanying drawing in the manner following:

Figure 1 illustrates the pencil partly in side elevation and partly in longitudinal section;

Fig. 2 is an enlarged fragmentary sectional view in the region surrounding the lower end of the pencil magazine;

Fig. 3 is a transverse section on line 3—3 of Fig. 2; and

Fig. 4 is a view of the plate which constitutes the magazine bottom.

The pencil herein shown comprises a body A having at its lower end a tip B through which a lead C is projected for use. A suitable lead propelling mechanism may consist of a long tube 5 which is extended through a bore formed axially of the body, the tube connecting at one end with the tip and having its other end 6 spun out to overlie a cap 7 which is fitted to the upper end of the pencil body. In its lower region the tube walls are given a non-circular formation as by flutings 8 with which may co-operate the flattened head 9 of a threaded plunger 10 (see Fig. 2). The plunger which is longitudinally movable within the tube is adapted to push with its nose 11 the lead C in ad-

vance of itself. Owing to the co-operation between the plunger head and the tube flutings the plunger is held against rotation while executing its longitudinal movements, which latter are imparted to it through the medium of a rotatable sleeve 12 having one portion of its walls internally threaded as at 13 so as to engage the plunger. The sleeve which lies within the upper region of the tube carries at its outer end a head 14 having a slip connection with a collar 15 which is adapted to be screw-threaded on the cap. The propelling mechanism just described forms no part of this invention, but is adverted to in order that the features which are special to my invention may be better understood.

Extending radially from the bore within the pencil body are a plurality of slots 20 each open at the upper end of the body where the cap is suitably apertured to preserve access thereto. By this means magazine chambers are provided, being conveniently formed by a broaching operation, which, of necessity, leaves the lower ends tapered inwardly as at 21. For the several slots thus produced, I provide a common bottom in the form of a plate 22 (see Fig. 4) having arms 23 extended radially, one to lie in each of the several slots 20. The plate is formed also with a central opening 24 of such contour as to fit non-rotatably around the fluted walls of the tube, as clearly shown in the drawing. If these flutings take the form shown in Fig. 3, a square hole in the plate will answer the requirements of this invention, as the plate will then have the effect of locking the tube against rotation within the pencil body. Should the flutings impart to the tube a cross sectional contour of different character, then the hole in the plate should be modified accordingly.

With the parts constructed in this manner, the plate is slipped into place, so that each of its arms 23 is disposed in one of the magazine slots. The plate is then wedged into final position so as to rest upon shoulders 25 which tend to form as the body material is displaced with this operation. When so positioned, the tube is introduced in place, being entered through the hole in the plate so as to lock non-rotatably therewithin.

By this invention I have simplified and

made sure the locking connection between the long tube and the pencil body. It is necessary that the tube maintain such a stationary relation, inasmuch as its fluted walls are required to resist rotation of the plunger when the pencil head is turned for the purpose of advancing the lead. Not only does the plate assure a positive locking connection with the tube, but it provides at the same time a transverse bottom for the several chambers forming the magazine. This double function is subserved most satisfactorily, inasmuch as the flutings are extended preferably throughout the lower half of the tube and the magazine throughout the upper half of the body, the plate being thereby permitted to occupy a convenient intermediate position, as shown. The several magazine chambers are by this construction given a sufficient length for the accommodation of reserve leads D, such as are shown in Fig. 2.

I claim:

1. A pencil comprising in combination a body having an axial bore provided with a plurality of longitudinally-extending grooves which open into said axial bore, said grooves providing reserve lead chambers, a tube within the bore and containing lead propelling mechanism, said tube, when in place, serving to close off the respective reserve lead chambers, and a plate non-rotatably connected with said tube and having projections shaped to enter the said

grooves to provide a bottom wall therefor and to prevent rotation of said tube.

2. A pencil comprising a body in which is an axial bore provided with a plurality of radiating slots extending downwardly into the body, a tube arranged within the bore and adapted to close off each slot from the others, a plate adapted to surround the tube and engage non-rotatably therewith, and having a projection which extends into each slot to provide a bottom therefor, and lead propelling mechanism within the tube operable by rotary means exteriorly of the pencil, substantially as described.

3. A pencil comprising a body in which is an axial bore provided with a radial slot extending downwardly from the upper pencil end, the lower end of the slot being tapered toward the bore, a tube containing lead propelling mechanism arranged within the bore and having an angular outer surface adjacent the lower slot end, and means adapted to prevent rotation of the tube within the body comprising a plate formed to surround the tube and engage non-rotatably therewith adjacent its angular portion and having a projection extending into the slot such as to provide a transverse bottom therefor, the plate when forced against the tapering end of the slot being wedged immovably in place, substantially as described.

IRVING L. POMEROY.
